UNITED STATES PATENT OFFICE.

SAUL BLICKMAN, OF NEW YORK, N. Y., ASSIGNOR TO SOPHIA BLICKMAN, OF BROOKLYN, NEW YORK.

DESIGN FOR A BOWL.

56,272.

Specification for Design. Patented Sept. 14, 1920

Application filed July 31, 1920. Serial No. 400,401. Term of patent 3½ years.

To all whom it may concern:

Be it known that I, SAUL BLICKMAN, a citizen of the United States, and resident of the city and State of New York, have invented a new, original, and ornamental Design for Bowls, shown in the accompanying drawing, forming a part of this specification, said drawing comprising a perspective view of a bowl embodying my design.

What I claim is:

The ornamental design for a bowl as shown.

SAUL BLICKMAN.
